SOCKET FOR TUBE TYPE INCANDESCENT LAMPS

Ruben P. Rosen, Philadelphia, Pa., assignor to
Progress Manufacturing Company, Inc., Philadelphia, Pa., a corporation of Pennsylvania

Application May 20, 1949, Serial No. 94,355

2 Claims. (Cl. 200—51.09)

1

This invention relates generally to electrical lamp sockets and more particularly to an improved construction of an electrical socket designed to operatively receive the end of a tube type incandescent lamp.

Heretofore and prior to the present invention considerable difficulties have been encountered in connection with the removal and replacement of tube type incandescent lamps from and into their end-receiving sockets. The sockets or lamp-holders conventionally employed at the present time include special receptacles for removably receiving end caps which are snap-fitted on the metal ends of the tube lamp, and in order to remove a lamp from between such conventional holders it becomes necessary to also remove the end caps from their respective receptacles. Inasmuch as these end caps are snap-fitted onto the ends of the lamp, it frequently occurs that they are inadvertently discarded together with the burnt-out lamp, with the result that the lampholders, in the absence of such end caps, were rendered useless for receiving and holding the lamp operatively therebetween.

Among the principal objects of the present invention is the provision of a lampholder or socket for the end of a tube type incandescent lamp in which all of the component parts thereof are arranged in the form of a single assembly, thereby avoiding the necessity of removing any component part for removal of the lamp therefrom and thus insuring against inadvertent loss of an essential part of the lamp holder.

Still another object of the present invention is to provide a lamp-holder of the character described having as a component part thereof a spring-biased socket for receiving one end of a tube type incandescent lamp, the socket being axially movable along the axis of the tubular lamp to an extent sufficient to free the opposite end of the lamp from its seating engagement with a relatively fixed socket mounted in spaced, coaxial alignment with the spring-biased movable socket.

Other objects and advantages of the present invention will appear more fully hereinafter, it being understood that the present invention consists substantially in the combination, construction, location and relative arrangement of parts, all as described in detail hereinafter, as shown in the accompanying drawings and as finally pointed out in the appended claims.

In the accompanying drawings, which are illustrative of a preferred form of the present invention,

2

Figure 1 is a perspective view of a lighting fixture showing a tube type incandescent lamp operatively supported between a pair of lamp-holders one of which is provided with a spring-biased type socket part in accordance with the present invention;

Figure 2 is a perspective view, partially in section, of the relatively fixed uppermost socket or lamp-holder shown in Figure 1;

10 Figure 3 is an exploded view showing in perspective the component parts of the assembly shown in Figure 2;

Figure 4 is a side elevational view of the aforesaid lamp-holder having the spring-biased socket part;

Figure 5 is an end elevational view thereof;

Figure 6 is a perspective view, partially in section, of the lamp-holder shown in Figures 4

and 5;

20 Figure 7 is an exploded view showing in perspective the component parts of the lamp-holder assembly of Figure 6; and

Figure 8 is a perspective view of the lower end portion of the movable socket part of said lamp-

25 holder assembly of Figure 7.

Referring now more particularly to the drawings, it will be observed that the lamp holder of the present invention is adapted for use in a lighting fixture as shown in Figure 1, said lighting fixture having a main supporting base 10 designed for use in conjunction with a tube-type incandescent lamp 11 the opposite ends of which are respectively received by a pair of axially spaced socket parts 12 and 13, the socket part 12 being immovably fixed in position upon the supporting base 10 of the lighting fixture, while the socket part 13 constitutes a relatively movable element of a lamp holder assembly, designated generally 14, constructed in accordance with and embodying the principles of the present invention.

The relatively fixed socket part 12 essentially includes a main body part 15 suitably molded or otherwise formed of insulating material, said 45 insulating body being provided therein with a socket 16 adapted to receive one of the ends of the tubular lamp 11. The base of this socket 16 is fitted with a metal contact plate 17 having a raised central portion 18 adapted to engage 50 and make contact with the metal cap (not shown) conventionally fitted on each end of the lamp. The contact plate 17 is so secured in the base of the lamp receiving socket 16, as by pins 17a—17a, as to permanently engage an electrical 55 contact element 19 extending laterally of the base

of the socket 16, its outer end being adapted for securement by soldering or welding, as at 20, to an insulated conductor 21, while its inner end is reversely turned, as at 22, for spring-pressed electrical engagement with the underside of the contact plate 17. The integrally formed supporting base 23 of the fixed socket 12 is provided in its rear face with a pair of interiorly threaded inserts 23^a—23^a for respectively receiving a pair of securing screws 24 which are projected through suitable holes 25—25 formed in the supporting base of the lighting fixture. It will be understood that the socket part 12 is fixed to the mounting base of the fixture with the axis of its socket 16 extending lengthwise of the fixture, that is, coincident with the axis of the tube lamp adapted to be supported between the oppositely disposed socket parts 12 and 13.

The lamp holder 14, of which the socket part 13 forms a component element, includes a supporting back plate 26, preferably but not necessarily formed of metal, which back plate is adapted to be fixedly secured to the supporting base 10 of the lighting fixture by a pair of screws 27—27 projected through openings 28 formed in the base 10 and into threaded apertures 29—29 formed in the supporting back 26. This supporting back is provided along its opposite edges with channel-shaped guide ways 30—30 and at its top with a horizontally disposed plate 31 terminating in a vertically disposed flange 32 extending between the forwardly disposed channel-forming flanges 33—33. The horizontally disposed top plate 31 is provided with a pair of laterally spaced struckout portions forming a pair of spring suspension hooks 34—34 from which are respectively suspended a pair of coiled tension springs 35—35.

Slidably associated with the supporting back 26 is a member 36 molded or otherwise suitably formed of insulating material, said portion being provided with a generally circular part 37 which is centrally recessed to provide a socket 38 for receiving one of the ends of the tubular lamp 11, and with an integrally formed rear part 39 adapted to be slidably received within the channeled supporting back 26. It will be noted that the rear part 39 of the member 36 is generally of rectangular form, the opposite longitudinal edges 40—40 of which are respectively adapted for sliding fit within the channels 30—30 of the fixed member 26. It will be noted also that the upper end of the member 39 terminates in a plane spaced below that of the upper end of the socket 38 so that when the member 36 is slidably fitted within its support 26 and shifted therein to its uppermost position, the upper end of the back part 39 of the socketed member 36 is engaged by the lower edge of the depending flange 32 of the member 26 to thereby limit upward movement of the socketed part 36 relatively to its support 26.

Extending across the bottom end of the guided part 39 of the socketed member 36 is a plate 41 having a pair of laterally spaced hooks 42—42 formed thereon, these hooks being extended upwardly through suitable openings 43—43 formed in the bottom end of the part 39 for respective engagement by the lower ends of the coiled extension springs. These springs thus operate to draw the socketed part 36 upwardly within its channeled supporting member 26, the normal fixed position of the latter relatively to the fixed socket part 12 being such that when its associated socketed part 36 is drawn into its normal position by the springs 35—35 the axially aligned sockets 16 and 38 are relatively so spaced apart

as to respectively embrace opposite ends of the tubular lamp 11. Thus, when it is desired to remove or replace the tubular lamp so normally received between the axially aligned socket parts 12 and 13, it only becomes necessary to shift the latter relatively to its fixed support 26 against the normal bias of the coiled springs 35—35 to thereby free the socket part 12 from the end of the tubular lamp received therein, the lamp being thereupon readily removed from between its supporting socketed holders.

It will be observed that whereas the relatively fixed socket part 12 is internally fitted with an unswitched contact element for electrically connecting the inserted end of the tubular lamp to the conductor 21 immediately upon insertion of the lamp end into the socket 16, the movable socket part 13 of the lamp holder assembly 14 is internally provided with a rotatable fixture switch 20 as well as with an interlock switch which is operative to open the circuit to the lamp when the socket part 13 is retracted into lamp removing position. Thus, referring more particularly to Figures 6 and 7, it will be noted that the base of the socketed member 36 is centrally bored, as at 44, to receive a rotatable switch knob 45, the inner end of which is kerfed, as at 46, to receive an S-shaped contact element 47. The opposite ends of this rotatable contact element 47 are respectively adapted to engage the arcuately shaped portions 48—48 of a pair of contact members 49 and 50 fixed in the base of the socket 38, the member 50 being provided with a wing element 51 the free end of which is adapted to project 30 upwardly through an opening 52 formed in an insulating plate 53 overlying the elements 49 and 50. The arcuately shaped parts 48—48 of these fixed contact elements 49 and 50 are disposed in diametrically opposed relation within a suitable 40 well 54 formed in the base of the socket 38. A metal contact plate 55 overlies the insulating plate 53 and is in electrical contact with the wing element 51 projecting upwardly through the opening 52 in the intervening insulating plate 53. A plate 55 is centrally provided with a raised portion 56 adapted for contact by the metal cap (not shown) fitted on the end of the tube lamp. The several parts 45, 47, 49, 50, 53 and 55 are all secured in their fixed relation, as shown, within 50 the base of the socket 38 by suitable securing elements, such as pins 57—57 driven into the member 36 through suitably registering apertures in the members 53 and 55.

The member 49 is provided with a lateral extension terminating in a freely extending lip 58 projecting externally of the socket 38 through an opening 59 formed in the back wall portion thereof, said lip 58 being adapted to wipingly engage and make electrical contact with a brush 60 type contact member 60 suitably staked to an insulator pad 61 fixedly secured in turn to the channeled support 26, the said pad 61 being secured to the channeled support by rivets 62 or the like. A guard plate 63, also formed of insulating material, is disposed to the rear of the insulating pad 61 and is provided with an upper lip 64 which projects through a slot 65 formed in the insulating pad to extend across the top of the brush contact 60 to prevent accidental contact therewith. The brush contact 60 is connected, as by soldering or welding to the terminal end of an insulated conductor wire 66.

When the tubular lamp 11 is mounted in position between its lamp holders 12 and 14, as shown 75 in Figure 1, the socketed part 13 of the lamp

holder 14 is normally biased by the coil springs 35 into its upper lamp-engaging position and so holds the lamp securely between its axially aligned, opposed holders. In such condition of the lamp holder 14, the contact member 49 is in electrical engagement with the brush contact 60 (as see Figure 6). With the members 49 and 60 in contact with one another, the lamp may be turned on and off by rotation of the rotary switch element 41, the lamp being on when said switch element is in bridging contact across the arcuate portions 48-48 of the contact members 49 and 50.

When it is desired to remove or replace the lamp, the lamp and the socketed part 13 of the lamp holder 14 are together axially shifted against the biasing tension of the coil springs 35-35 into their full line position shown in Figure 4, whereupon the upper end of the lamp 11 is free to be swung outwardly of the relatively fixed lamp holder 12 and thence axially out of the relatively movable socketed part 13 of the lamp holder 14. Upon axially shifting the socketed part 13 of the lamp holder 14 into its lamp removing position, as shown in Figure 4, lip 58 of the contact member 49 is disengaged from the relatively fixed brush contact 60 in consequence of which the connection to the lamp is broken. If desired, and it is generally preferable so to do, the brush contact 60 is so arranged with respect to the lip 58 movable with the socketed part of the lamp holder 14 as to provide for breaking of the circuit to the switch contact 49 when the socketed part is completely free of its lamp and is thus in its uppermost position. In such case, the lip 58 of the switch contact member 49 would be spaced above the brush contact 60, engagement with the brush contact being then normally made only when the socketed part of the lamp holder 14 is in the lamp supporting position.

It will be understood, of course, that the present invention is susceptible of various changes and modifications which may be made from time to time without involving any departure from the general principles or real spirit thereof, and it is accordingly intended to claim the same broadly, as well as specifically, as indicated in the appended claims.

What is claimed as new and useful is:

1. A holder for a tubular incandescent lamp comprising, in combination, a fixed support for a lamp socket member, a lamp socket member slidably associated with said support for rectilinear movement relatively thereto along the longitudinal axis of the tubular lamp supported by said socket member, said socket member having an open-ended circular recess therein for receiving one end of said tubular lamp, a contact plate in the base of said lamp-receiving recess, a pair of spaced contact elements arranged beneath said plate with one of said elements in electrical contact therewith, a rotary switch element interposed between said spaced contact elements for opening and closing the electrical circuit therebetween, one of said contact elements including an extension projecting laterally of the socket with its outer end terminating short of said fixed support for the slidable socket member, and a brush contact element fixedly associated with said support and adapted to engage said terminal end of said laterally extended contact element to provide conjointly with the latter a safety interlock switch operative to close the circuit to said lamp socket contact plate only when said lamp socket is in a predeterminedly fixed position relative to its support.

2. In a holder for a tubular lamp as defined in claim 1, wherein said safety interlock switch is interposed between said slidable lamp socket and its support, said switch being opened or closed accordingly as said lamp socket is shifted relatively to its support.

RUBEN P. ROSEN.
